CAMERA CARRYING CASE

Vincent F. Lang, Rochester, and Edward Emison, Ontario,
N.Y., assignors to Eastman Kodak Company, Rochester,
N.Y., a corporation of New Jersey

Filed Feb. 17, 1964, Ser. No. 78,671

Term of patent 14 years

(Cl. D61—1)

FIG. 1

FIG. 4

FIG. 2

FIG. 5

FIG. 3

FIG. 6

FIG. 7

FIG. 1 is a top plan view of a camera carrying case in a closed condition, showing our new design;
FIG. 2 is a front elevational view thereof;
FIG. 3 is a rear elevational view thereof;
FIG. 4 is a left end elevational view thereof;
FIG. 5 is a right end elevational view thereof;
FIG. 6 is a bottom plan view thereof; and
FIG. 7 is an end view thereof in a fully open condition.

The camera shown in broken lines in FIG. 7 is for illustrative purposes only.

We claim:

The ornamental design for a camera carrying case, as shown and described.
